INVENTOR

UNITED STATES PATENT OFFICE

95,912

DESIGN FOR A COMBINED WALL SHELF AND RADIOCABINET

Delwin W. Kussman, Racine, Wis.

Application April 10, 1935, Serial No. 56,295

Term of patent 7 years

To all whom it may concern:

Be it known that I, Delwin W. Kussman, a citizen of the United States, residing at Racine, in the county of Racine and State of Wisconsin, have invented a new, original, and ornamental Design for a Combined Wall Shelf and Radio Cabinet, of which the following is a specification, reference being had to the accompanying drawing, forming part thereof.

The drawing is a view in perspective of a combined wall shelf and radio cabinet embodying my design.

I claim:

The ornamental design for a combined wall shelf and radio cabinet, as shown.

DELWIN W. KUSSMAN.
